UNITED STATES PATENT OFFICE

CLIFFORD NORTON, OF SOUTH ORANGE, NEW JERSEY, AND JOHN G. GUSTAFSON, OF NEW YORK, N. Y., ASSIGNORS TO GRAHAM & NORTON COMPANY, OF NEW YORK, N. Y., A CORPORATION OF DELAWARE

AUTOMATIC STOP FOR RECIPROCATING DEVICES

Application filed June 5, 1925. Serial No. 35,244.

Our invention relates to an improved automatic stop device designed to lock a reciprocating member to which it is attached against movement in one direction but to allow free movement in the opposite direction and more particularly to devices wherein the reciprocating member carries a pivoted locking dog or latch which co-operates with a fixed stop and is arranged to ride upon said stop in both directions of movement as well as to pass said stop freely on movement in one direction and to lock against said stop on movement in the opposite direction.

Our invention is designed especially to provide a simple and compact construction insuring a change in position of said locking dog or latch on continuation of movement of the supporting member past the locking position, such change of position being effective to permit the latch to pass the locking position freely on the reverse movement of its supporting member. A further object is to insure a change of position of the latch such that its supporting member may move freely in one direction without obstructing the latch until the locking position is attained where the dog will lock against reversal of movement.

For convenience of description the motion in one direction will be termed the "forward movement" and the reverse motion or motion in the opposite direction will be termed the "backward movement".

This invention consists in the provision of fixed lugs provided as hereinafter described to be engaged by the latch at the desired stages of the forward and backward movements to insure said changes of position of the latch, all as will be hereinafter more particularly described in connection with the accompanying drawings wherein:

Fig. 1 shows the parts in side elevation in position for free forward movement past the stop.

Fig. 2 shows the position of the same parts as the latch begins to be passed through the throat on the forward movement wherein the actuating lugs or ears are located.

Fig. 3 shows a position of the reciprocating device and pivoted locking dog or latch at which the latch will lock upon attempt to

move the support in the backward direction.

Fig. 4 shows the said parts after the latch-carrying member has moved sufficiently in the forward direction to free the latch from the throat and allow it to be moved to position such that it may pass freely through the throat on the backward movement.

Fig. 5 shows the latch in position as it is about to enter the throat on the backward movement.

Fig. 6 shows the position of the latch as it is about to pass the shoulder of its stop on the backward movement.

Fig. 7 shows the parts at a slightly more advanced stage of the backward movement than that shown in Fig. 6.

Fig. 8 shows the locking dog or latch about to leave the throat and preparatory to moving down into position such as indicated in Fig. 1.

Fig. 9 is an edge view and partial section through a supporting member of the latch.

In the drawings:

1 indicates a reciprocating member which carries a locking dog or latch indicated at 2. Said dog or latch is pivotally mounted at 3 so that it may take or be moved into the various positions shown in the drawings. The arrow 4 shows the direction of the forward movement or motion herein referred to and arrow 5 in the various figures shows the direction of the backward or reverse movement.

The stop with which the latch co-operates is shown at 6 and is formed preferably as a shoulder or offset on a fixed member consisting preferably of a solid block or casting 7 adapted to be firmly secured as indicated by screws or other devices to a fixed support. Said stop 6 extends upwardly toward the path described by the latch when moved by said reciprocating member 1. Said casting 7 is also provided with the downwardly projecting lugs or ears 8 and 9 located above the throat or opening 10 in said block or casting through which the latch passes in the forward and backward movements.

Said lugs 8 and 9 are located as shown respectively at opposite sides of the vertical line passing through the stop 6.

The use of the lug 8 is to engage an inclined edge of the latch and to force the same down-

wardly towards the rail or floor 11 on the casting, after the latch 2 leaves the stop 6 in passing to position for being locked against reverse movement of the member carrying the latch. This action of the lug 8 insures that 5 after the latch has moved to position over said rail the member 1 will be locked against backward movement by the locking dog engaging the vertical side of the shoulder or stop 6. When the latch reaches the end of the rail 11 10 the lug 8 insures its movement downwardly towards position such as shown in Fig. 4 so that on backward movement the latch may pass freely through the throat without being stopped by the shoulder at 6, this free movement being due to the fact that the incline 12 on the latch will ride freely when it engages the shoulder 13 and the top edge of the shoulder or stop 6.

20 On this backward movement the bottom edge of the latch finally passes shoulder 6 and the latch may then be swung downwardly to position as indicated in Fig. 8 and will pass out of the throat on the continuation of the backward movement and may take the position shown in Fig. 1.

30 The function of the second lug or ear 9 is to positively move the latch downward on such backward movement through engagement of said lug with the incline 14 on the latch.

35 In the forward movement the latch passes through the throat by riding upon the incline at the back side of the lug or shoulder 6 as indicated in Fig. 2 and finally passes to position where it is sustained upon the rail 11. At this stage of the forward movement an attempt to move the support 1 in a backward direction will result in the locking of the dog or latch against the stop. By continuing 40 the forward movement, however, until the toe of the dog passes off the rail and said dog or latch is swung downwardly to position shown in Fig. 4, backward movement can take place, the inclined side 12 then riding shoulder 13, and stop 6. The movement 45 through the throat takes places as indicated in Figs. 5, 6 and 7. The backward movement may continue until the parts assume the position in Fig. 1 ready for a new forward movement.

50 In the backward movement just described the function of the lug 9 in connection with the latch will be readily understood by reference to Fig. 8 which illustrates the position 55 of the parts after the incline on the latch has encountered the lug 9 preparatory to being thrown down into position such that it may move freely through the throat on repetition of the forward movement.

60 What we claim as our invention is:—

1. In an automatic locking dog or latch device, the combination with a reciprocating member and latch carried thereby, of a fixed member having a passageway through which 65 the latch has a reciprocating movement, a

stop on one side of the line of movement of the latch and projecting towards the path thereof and adapted to allow free forward movement of the latch but to check the backward movement from a position at a predetermined stage of said forward movement and a lug or ear projecting toward the path of movement of the latch from the side thereof opposite said stop and adapted to be engaged by the latch on continuance of the forward movement thereof past the stop for throwing said latch positively into such position that it will engage the locking shoulder or stop on the attempt to reverse the movement of the reciprocating member. 70 75 80 85

2. In an automatic locking dog or latch, the combination of a fixed member having a throat or opening adapted to allow passage of said locking dog or latch and a movable member carrying the latch and reciprocating the same through said passageway and three fixed shoulders or lugs one located on one side of said passageway and projecting toward the path of movement of the locking dog or latch and co-operating therewith to 90 check the backward movement while the two others project toward the path of movement of the latch from the opposite side of said path and are arranged to engage the latch after it passes the stop and act respectively 95 thereon one to throw the same by positive action into position such that it may ride freely in a backward direction over the stop and the other, acting on the latch after it passes the stop in said backward movement, to throw the same positively into normal position for a repetition of the said movement past the stop into position for relocking. 100

3. In an automatic stop device embodying 105 a fixed member, a locking dog or latch mounted to be capable of movement on a reciprocating member through a throat or passageway in said fixed member, a fixed stop projecting toward the line of movement of said reciprocating dog or latch from one side of said line and co-operating with said latch to check the backward movement while allowing free forward movement and a lug projecting into the throat or passageway towards the line or 110 path of movement of the locking dog or latch from the opposite side of said line and in position to be engaged by the latch on forward movement beyond the position where it escapes by the fixed stop and acting thereon to force it down into position such that on the reverse movement of the reciprocating member the dog may ride freely over the locking shoulder or stop instead of locking 115 against the same. 120

4. In an automatic stop device embodying 125 a locking dog or latch mounted to be capable of movement on a reciprocating member into and out of locking position, a fixed stop over the locking shoulder of which the latch rides 130

in movement of the reciprocating member both forwardly and backwardly, said stop co-operating with said latch to check the backward movement while allowing free forward movement and a lug projecting towards the path of the latch from the side of said path opposite that on which the fixed stop is located and adapted to engage said latch after it passes this stop on the free backward movement and co-operating therewith to throw it into position preparatory for a repetition of the forward movement.

5. In an automatic stop device, the combination with a reciprocating member and latch mounted thereon, of a fixed member providing a throat through which the latch passes in the backward and forward movements of said member, said member being provided with a locking dog or shoulder engaged by one side of the latch, and two lugs adapted to engage the other side of the latch, and operating to throw the latch downwardly after it passes the locking shoulder or stop in the forward and backward movements respectively.

Signed at New York, in the county of New York and State of New York, this 13 day of April, A. D. 1925.

CLIFFORD NORTON.
